Primary Examiner — Lauren D Mcvey*Assistant Examiner* — Sarah L Smith(74) *Attorney, Agent, or Firm* — Scherrer Patent & Trademark Law, P.C.; Stephen T. Scherrer; Monique A. Morneau(57) **CLAIM**

The ornamental design for the art sword, as shown and described.

DESCRIPTION

FIG. 1 is a perspective view of the art sword in an open position in accordance with the present invention;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front view of the art sword in FIG. 1 in a closed position.

The broken lines in the drawings show portions of the art swords that form no part of the claimed design.
